A. R. PERRIN

SLUB CATCHER

Filed April 28, 1925.

UNITED STATES PATENT OFFICE.

ALPHONSE R. PERRIN, OF WESTBROOK, MAINE.

SLUB CATCHER.

Application filed April 28, 1925. Serial No. 26,475.

The invention relates to a slub catcher for winding machines.

The object of the present invention is to provide a simple, practical and efficient slub

5 catcher of strong, durable and inexpensive construction designed for use on various types of yarn guides of winding machines and equipped with a feeler finger having a slot for the passage of the yarn and having 10 a pivotal movement laterally of the yarn and a swinging movement in the direction of the travel of the yarn and adapted to yield readily to the movements of the yarn and practically float with the same whereby the 15 slot in the feeler finger for the passage of the yarn may be made much narrower than the slot in the yarn guide to enable the feeler finger without liability of chafing the yarn to have a yarn passage slot sufficiently narrow 20 to engage slubs and similar imperfections in the yarn and cause a breaking of the yarn to prevent such imperfections passing on to the spool.

A further object of the invention is to provide a delicate and sensitive slub catcher of 25 this character capable of automatically assuming a position to enable the yarn to be readily introduced into its passage or slot after a slub or other imperfection has been 30 removed and the yarn tied in the customary manner.

With these and other objects in view, the invention consists in the construction and novel combination and arrangement of parts 35 hereinafter fully described, illustrated in the accompanying drawings and pointed out in the claims hereto appended, it being understood that various changes in the form, proportion and minor details of construction, 40 within the scope of the claims, may be resorted to without departing from the spirit or sacrificing any of the advantages of the invention.

In the drawings:—

45 Figure 1 is a perspective view of a slub catcher constructed in accordance with this invention and shown applied to a yarn guide.

Fig. 2 is a vertical sectional view through 50 the yarn guide and the bracket of the slub catcher.

Fig. 3 is a detail sectional view illustrating the manner of clamping the yarn.

55 Fig. 4 is a sectional perspective view showing a portion of the guide rod, the feeler finger and the yarn guide, the spaces be-

tween the said parts being exaggerated for convenience of illustration.

Fig. 5 is a perspective view of the slub catcher detached.

Fig. 6 is a vertical sectional view of a different type of yarn guide equipped with a slub catcher embodying a modification of the invention.

Fig. 7 is a similar view illustrating the manner of clamping the yarn.

Referring particularly to Figs. 1 to 5, inclusive, of the drawings, the slub catcher comprises in its construction a supporting bracket 1 of approximate L-shape, constructed of suitable metal and consisting of a vertical 70 attaching portion and spaced horizontal projecting arms 2 between which is pivoted the upper end of a depending link 3 adapted to swing longitudinally of the yarn 4. The bracket 1 is secured by a screw 5 or other suitable fastening means to the upper portion of the frame or body 6 of a yarn gripper. The spaced arms 2 are provided at their outer ends with aligned transverse perforations for the reception of a pin 7 or other suitable pivot on which the link is mounted.

The link is preferably recessed at 8 as shown and it has mounted on its lower recess portion a screw 9 forming a pivot for a pendant laterally and longitudinally swinging feeler finger or member 10 provided at its upper end with a suitable perforation for the pivot 9. Instead, however, of employing a screw, any other suitable form of pivot may, of course, be used as will be readily understood. The feeler finger which is normally maintained in a vertical position by the yarn is provided at its lower portion with a vertical slot 11 extending longitudinally of the lower portion of the feeler finger and forming a passage for the yarn and arranged at right angles to the horizontal slot or passage 12 provided in the yarn gripper for the passage of the yarn. The feeler finger is provided

at the inner side of the slot 11 with an extension 13 which forms a guide for introducing the yarn into the slot and the feeler finger is provided at its pivot with a laterally extending weighted arm 14 preferably arranged at right angles to the feeler finger and adapted to cause the feeler finger to swing laterally outwardly to the open side of the yarn gripper abutting relation with a stop 15 as illustrated in dotted lines in Fig. 1 of the drawing to arrange the slot 11 in

convenient position in the introduction of the yarn. The open lower end of the slot 11 when the feeler finger is in the dotted line position of Fig. 1, is in line with the slot 12 of the yarn gripper and it is only necessary to introduce the yarn into the slot 12 of the yarn gripper and move the yarn inwardly into engagement with the extension 13 and a further movement of the yarn laterally towards the center of the yarn gripper will swing the feeler finger from the dotted inclined position to the full line vertical position shown in Fig. 1 automatically carrying the yarn into the slot 11. The feeler finger is provided intermediate of its ends with a bend 16 to offset the lower portion from the plane of the upper portion and arrange the said lower portion close to the yarn gripper and the said offset lower portion of the feeler finger is provided with a projection 17 which is rounded at the end and which fits against the yarn guide.

The yarn gripper comprises in its construction the said frame or body 6 having a clamp 18 for securing it to the guide rod 19 of a winding machine. The body 6 has mounted on it a lower fixed horizontal rod or member 19^a with which cooperates a swinging member consisting of a frame 20 mounted on a horizontal pivot pin 21 and carrying a yarn gripper plate 22 which cooperates with the fixed yarn gripper member 19^a. The plate 22 is secured to opposite side portions 23 of the movable frame 20 of the yarn gripper by screws 24, one of which is utilized for securing the stop 15 to the movable plate or member of the yarn gripper. The movable member or plate of the yarn gripper is normally maintained at a slight angle or inclination to arrange the lower edge of the plate 22 in spaced relation with the fixed gripper member 19^a to provide a slot or passage for the yarn and the said hinged member of the yarn gripper is adapted to swing on the horizontal pivot 21 to clamp the yarn against the fixed gripper member 19^a to clamp and break the yarn. The hinged frame of the yarn gripper is normally maintained in an inclined position by a coiled spring 25 which is adapted to yield to permit the movable member 22 to clamp and break the yarn when the feeler finger is engaged by a slab.

The slab 26 or similar imperfection caused by a particle of cotton or other material getting into the yarn produces a soft place in the yarn and in passing over the gripper rod 19 will be flattened and in attempting to pass through the narrow vertical slot of the feeler finger will be caused to turn or twist which will also tend to scrape the loose fibers and increase the size of an obstruction and thereby produce a more positive operation of the device in causing a clamp of the yarn and a breaking of the same. Ow-

ing to the extreme lightness and sensitivity of the feeler finger, it is adapted to yield readily to the movements of the yarn incident to the vertical or up and down motion of the yarn gripper without friction on the yarn or causing any chafing of the same. It is maintained in constant touch with the yarn by the action of the weighted arm 14. By reason of this floating action and light structure and the ready yielding of the feeler finger and the movements of the yarn, the vertical slot in the feeler finger may be made sufficiently narrow to catch slubs without chafing the yarn which cannot be done with the slot of the yarn gripper owing to the heavy rigid construction of the same. The feeler fingers will be provided with slots of different widths to suit the yarn passing through the yarn gripper and the slot 11 of the feeler finger 10 in the accompanying drawings as designated on the weighted arm ten one-thousandths (.010). The pivot screw 9 will enable the feeler finger to be readily changed so that the feeler finger having a slot of the required width may be readily applied to the device.

The stop 15 may be of any desired construction and in the accompanying drawings it is shown as consisting of a wire having a coil or loop 27 clamped by the head of the screw 24. The feeler finger is permitted by the link 3 to swing upwardly to enable it to be readily cleaned and after cleaning it will assume by gravity its proper position with relation to the yarn gripper for enabling the yarn to be readily placed in the same and in the slot 11.

When the device is applied to an old style yarn guide of the Draper or similar type not equipped with a swinging portion operable by the yarn for clamping the latter, the feeler finger is preferably constructed as illustrated in Figs. 6 and 7 of the drawings. In this form of the invention the feeler finger 28 is provided with a spring member 29 bowed in the opposite direction to the bend 30 of the feeler finger and having its lower end 31 normally located slightly above the yarn. The guide rod 32 will be provided with a slot 33 for maintaining the yarn to the feeler finger in a central position with relation to the yarn guide. The feeler finger when engaged by a slab or other imperfection as illustrated in Fig. 7 of the drawing, will be swung rearwardly and will compress the bowed resilient member 29 and straighten the same thereby extending the lower end thereof into clamping engagement with the yarn for clamping the yarn against the bottom of the yarn guide. This will cause a breakage of the yarn passing through the slot 34 of the yarn guide. The projection 17 is omitted but the feeler finger is otherwise constructed as heretofore described and will be equipped with the

weighted arm and be limited in its lateral swinging movement by the stop as heretofore described.

What is claimed is:

1. A slub catcher for yarn grippers having a slot, comprising a feeler finger pivoted above the slot of the yarn gripper and extending across the same and provided with a vertical slot forming a passage for the 10 yarn, said feeler finger being readily yieldable to the movements of the yarn.

2. A slub catcher for yarn grippers having a slot, comprising a feeler finger pivoted above the slot of the yarn gripper and extending across the same and provided with a 15 vertical slot forming a passage for the yarn, said feeler finger being readily yieldable to the movements of the yarn and the width of its slot being less than that of the yarn 20 guide.

3. A slub catcher for yarn grippers comprising a feeler finger extending across the yarn passage of the yarn gripper in approximately vertical direction and having a vertical slot for the passage of the yarn, and means for mounting the finger to permit the 25 same to swing both laterally and longitudinally of the yarn.

4. A slub catcher for yarn grippers comprising a feeler finger extending across the 30 yarn passage of the yarn gripper in approximately vertical direction and having a vertical slot for the passage of the yarn, and means for mounting the finger to permit the same to swing both laterally and longitudinally of the yarn, and yieldable means actuated by the feeler finger in its longitudinal swinging movement for clamping the yarn to break the same.

40 5. A slub catcher for yarn grippers comprising a feeler finger extending across the yarn passage of the yarn gripper in approximately vertical direction and having a vertical

slot for the passage of the yarn, and means for mounting the finger to permit the 45 same to swing both laterally and longitudinally of the yarn, and laterally extending weighted arms arranged to swing the feeler finger outwardly and a stop for limiting the movement of the feeler finger when actuated by the arms. 50

6. A slub catcher for yarn grippers including a feeler finger extending across the yarn passage of a yarn gripper and pivoted above the same and provided at its lower portion 55 with a slot and extended at the inner side of the slot to form a guiding portion, a weighted arm extending from the inner side of the feeler finger for swinging the same outwardly and a stop for limiting the movement of the feeler finger when actuated by the said arm. 60

7. A slub catcher for yarn grippers comprising a bracket, means for attaching the bracket to a yarn gripper at the upper portion thereof, a link pivoted to the bracket and arranged to swing longitudinally of the yarn, and a feeler finger pivoted to the link to swing laterally of the yarn and extending downwardly across the yarn passage of the 70 gripper and provided with a slot arranged at an angle to the yarn passage of the yarn gripper. 65

8. A slub catcher for yarn grippers, comprising a feeler finger pivoted at its upper 75 end to swing laterally of the yarn and provided at its lower portion with a slot forming a passage for the yarn and arranged at an angle to the yarn passage of the yarn gripper, said feeler finger having its lower 80 portion arranged adjacent the yarn gripper and provided with a projection normally resting against the yarn gripper. 80

In testimony whereof I have hereunto set my hand.

ALPHONSE R. PERRIN.
